UNITED STATES PATENT OFFICE.

ARVIN J. GORE, OF DENVER, COLORADO.

DESIGN FOR A GAME-BOARD.

57,430.

Specification for Design.

Patented Mar. 29, 1921.

Application filed December 18, 1916. Serial No. 137,729. Term of patent 3½ years.

To all whom it may concern:

Be it known that I, ARVIN J. GORE, a citizen of the United States, residing in the city and county of Denver and State of Colorado, have invented a new, original, and ornamental Design for Game-Boards, of which the following is a specification, reference being had to the accompanying drawing, forming part hereof.

The figure is a plan view of a game board, showing my new design.

I claim:

The ornamental design for a game board, as shown.

ARVIN J. GORE.
